UNITED STATES PATENT OFFICE.

JOHN H. BURKHOLDER, OF ASHLAND, OHIO, ASSIGNOR TO ELITE MANUFACTURING COMPANY, A FIRM COMPOSED OF JOHN H. BURKHOLDER, P. E. COUNTRYMAN, AND E. L. KILHEFNER, OF ASHLAND, OHIO.

VEHICLE JACK.

Application filed November 1, 1924. Serial No. 747,350.

To all whom it may concern:

Be it known that I, JOHN H. BURKHOLDER, a citizen of the United States, residing at Ashland, in the county of Ashland and 5 State of Ohio, have invented certain new and useful Improvements in a Vehicle Jack, of which the following is a specification.

My invention relates to an improvement in vehicle jacks, especially jacks comprising 10 two or more lift screws adapted to be extended to different heights, and in general my object is to simplify the construction of jacks of the type described to permit them to be readily manufactured, and as 15sembled, easily and safely operated, and conveniently handled. Thus the invention involves, among other things, the use of a hinged folding connection for the extensible parts of the jacks whereby at least one of the 20 parts may be prevented from turning while the screws are being operated. As arranged this folding connection limits the extensible movement of the parts and prevents the screws from separating and the jack from 25 collapsing, and it also provides a convenient hand grip for the jack adapted to facilitate its handling and placement beneath the vehicle.

In the accompanying drawings, Fig. 1 is 30 a side view, partly in section, of a jack embodying my improvement, with the lift members fully extended. Fig. 2 is a vertical sectional view of the same jack with its parts telescoped together.

Fig. 3 is a vertical section of a known type 35 of screw jack modified and equipped with a hinged folding connection for the upper lift screw according to my invention, and Fig. 4 is a side elevation of the same jack.

Fig. 5 is a vertical section of another 40 known form of jack embodying my improved folding connection, and Fig. 6 is a top view thereof. Fig. 7 is a side view, partly in section, of the jack shown in Fig. 5, but telescoped and showing the folding elements gripped within a hand as in carrying or placing the jack in position.

Now referring to Figs. 1 and 2, the jack shown therein, comprises a hollow standard 45 2 having a laterally extending arm 3 in which the operating shaft 4 of a bevel gear 5 is journaled. A second larger bevel gear 6 is rotatably seated upon the top of standard 2 in mesh with pinion gear 5, and a tubular

extension 7 integral with or rigidly secured 55 to large gear 6 projects into the hollow standard and rotates freely therein, and this extension 7 and its gear 6 may be lifted apart from the pinion gear and bodily removed from the standard when the various other parts of the jack are disconnected. A 60 separate screw member 8 is pinned or otherwise secured centrally to the base 9 of the standard and extends upwardly apart from the walls thereof. A sleeve member 10 having right and left screw-threads, internally and externally, is revolubly engaged with fixed screw 8, and a pair of laterally-extending lugs 12 at the lower end of sleeve 10 slide 65 vertically in correspondingly situated longitudinal channels 14 in the inner wall of the rotatable extension 7 which depends from gear 6. Consequently, when the bevel gears 70 rotate extension 7, screw or sleeve 10 is also rotated and moves upwardly or downwardly 75 on stationary screw 8 depending upon the direction of rotation of the operating gears. In order to increase the lifting range of the jack, a second lift screw 15 is sleeved in 80 screw-threaded engagement with inner screw sleeve 10, and tubular extension 7 is of sufficient diameter to receive upper lift screw 15 when the parts are telescoped together. The outer end of lift screw 15 may be variously 85 constructed to engage and support the object to be elevated, and unless this lift member is prevented from rotating during the 90 rotation of inner screw sleeve 10 and outer extension 7 no differential movement between the screws will occur. Of course when the standard is resting on the ground and the upper lift screw 15 is engaged with an object, such as the axle of a vehicle, the part 95 15 is held against rotation, but it is also true that lift screw 15 must be raised more or less in the first instance to bring about such an engaging and working relation. To prevent independent rotation of upper lift screw 15 and to obtain a constant working relation 100 between the two lift screws I provide a pair of hinged elements 16 and 17, respectively, and pivotally connect one of them to ears 18 at one side of the enlargement or top rest 19 of upper lift screw 15, and hinge the other to projections 20 integral with the upper end of standard 2. The hinge joint between the two folding elements 16 and 17 105 may be a shouldered joint as shown in Fig.

1 to prevent these parts from buckling too far inward, but in any event when the two movable lift screws are raised and separated a definite distance the hinged elements will 5 check their movements and prevent the screw members from separating and the jack from collapsing under a load. When these folding elements are folded or unfolded the operator may readily grasp them and carry 10 the jack around or set it or move it from place to place. Only a single pair of hinged connecting elements are shown in the present device, but it is obvious that two sets of such devices may be attached on opposite 15 sides of the standard if any advantage may be thereby gained. In some instances the folding connection may be diametrically opposite the operating shaft; in others it may be on the same side as the operating shaft, 20 or projected at any other angle or side of the standard.

The utility of similar folding elements in known types of double-screw jacks is shown in Figs. 3 to 7. Thus, in Figs. 3 and 4 I 25 show a lift screw 21 operating in a hollow standard 22 having a screw-thread 23 in its upper end. A second lift screw 24 is screw-engaged and telescopically connected with the upper end of lower screw 21. A 30 bevel gear 25 carried by screw 21 meshes with an operating pinion 26 journaled in one arm 27 of a yoke member and sleeve 27 which is slidably engaged with standard 22 and prevented from turning by lugs 28 on 35 the standard. A cover plate 29 confines gear 25 within the upper yoke portion of sleeve 27, and it should be noted that the gears and operating mechanism must necessarily rise and fall with screw 21. In this 40 type of double screw jack it is also desirable that rotation of the upper lift screw 24 be prevented, and this result may be readily accomplished with all the advantages hereinbefore described by attaching a set of folding links 16' and 17' to the top rest 19' of upper screw 24 and to cover plate 29 substantially as delineated. In another known 45 jack embodying two lift screws, see Figs. 5 to 7, the operating gearing 30 is mounted 50 upon the upper lift screw 31, and the housing 32 for such gearing contains an operating worm and shaft 33 to which an operating handle is connected, the handle being either a detachable or permanently connected part, not shown in the drawing. In 55 operating a jack of this type the handle is relied on to prevent independent rotation of the gear housing, but it will be seen that in applying power at the highest point of 60 the jack through an independently rotatable gear housing the stability of the jack is easily disturbed and its setting and handling made difficult. To overcome the objections in part, a pair of hinged links 16" and 17" 65 may be connected to housing 32 carried by

upper screw 31 and to the top of standard 34 in which the lower screw 35 operates.

What I believe to be new and novel and desire to claim, is:

1. A vehicle jack having a set of extensible screw and lift members, and means adapted to prevent at least one of said members from rotating while another is operating, comprising folding links secured to one member and another part of said jack. 70

2. A vehicle jack having telescopic screws and operating means for said screws, and a pair of hinged links connected to one of said screws and a non-rotatable part of said jack adapted to fold and unfold in operating 80 said jack.

3. A vehicle jack having movably-related parts comprising extensible screws and a supporting standard means carried by one of said parts adapted to rotate one of said screws, and a pair of hinged links connecting movably-related parts of the jack adapted to prevent rotation thereof when said screw is rotated. 85

4. A vehicle jack, comprising a standard, 90 a pair of extensible screws telescopically related to said standard, operating means for said screws carried by one of said parts, and a pair of hinged elements connecting relatively fixed and movable parts of said 95 jack and foldable and unfoldable at one side of said standard.

5. A vehicle jack, comprising a standard, 100 a pair of telescopic lift screws connected to operate together and jointly supported upon said standard, means connected with one screw adapted to rotate the same and there-through raise and lower the second screw, and means adapted to prevent the rotation of the second screw comprising a pair of 105 hinged links connected to the second screw and to a non-rotatable part of the jack.

6. A vehicle jack, comprising a standard, 110 a pair of telescopic lift screws supported upon said standard, means carried by one 110 of said parts adapted to operate said lift screws, and a pair of foldable links connecting the upper end of one of said screws with a non-rotatable part of said jack.

7. A vehicle jack, comprising a standard, 115 separate upper and lower lift screws telescopically mounted within said standard, means adapted to rotate one of said screws, and a pair of foldable links connecting the upper ends of a pair of the movably-related 120 parts of the jack.

8. A vehicle jack, comprising a hollow standard having a fixed screw therein, a double-screw threaded sleeve engaged with said fixed screw, a second lift screw engaged 125 with said sleeve, and a rotatable driving member surrounding said fixed screw having operable connection with said sleeve adapted to permit said sleeve to be rotated and elevated and lowered within said standard. 130

9. A vehicle jack, comprising a hollow standard having an upright screw centrally fixed therein, a sleeve screw-threaded internally and externally engaged with said fixed screw, a second lift screw sleeved in screw-engagement with said sleeve, a driving member for said sleeve rotatably supported upon said standard, and means adapted to prevent said second lift screw 10 from rotating while said sleeve is being rotated.

10. A vehicle jack, comprising a fixed vertical screw, a sleeve having inner screw-threads engaged with said screw and formed 15 with outer screw-threads, a second lift member screw-connected with said sleeve and a

rotatable gear having a depending driving part opposite said fixed screw adapted to be slidably engaged with said sleeve.

11. A vehicle jack, comprising a fixed vertical screw, a sleeve having inner screw-threads engaged with said screw and formed with outer screw-threads, a second lift member screw-connected with said sleeve, a rotatable gear having a depending driving part opposite said fixed screw adapted to be slidably engaged with said sleeve and a pair of hinged links adapted to prevent the second lift member from rotating while said sleeve is being driven.

In testimony whereof I affix my signature.
JOHN H. BURKHOLDER.
